The ornamental design for a golf putter head, as shown and described.

DESCRIPTION

FIG. 1 is a front elevational view of a golf putter head showing my new design;

FIG. 2 is a rear elevational view;

FIG. 3 is a front end elevational view;

FIG. 4 is a rear end elevational view;

FIG. 5 is a top plan view;

FIG. 6 is a bottom plan view; and,

FIG. 7 is a front perspective view.
The broken line showing of a shaft segment is for illustrative purposes only and forms no part of the design.

FIG.1

FIG.2

FIG.5

FIG.3

FIG.6

FIG.4

FIG.7
